UNITED STATES PATENT OFFICE.

FENWICK FAYETTE SAXE, OF NEW YORK, N. Y.

WINDOW CLEANER.

Application filed September 20, 1921. Serial No. 501,880.

To all whom it may concern:

Be it known that I, FENWICK F. SAXE, a citizen of the United States, residing at New York city, in the county of Bronx and 5 State of New York, have invented new and useful Improvements in Window Cleaners, of which the following is a specification.

This invention relates to window cleaners and particularly to mechanical means connecting interior and exterior cleaning devices so that the operation of one will effect the simultaneous and corresponding operation of the other.

The principal object is to produce a device of this nature which shall be simple of construction, cheap to manufacture, and highly efficient for the purpose for which it is designed.

Another object is to provide a novel and improved means for connecting and operating the interior and exterior cleaning devices.

With these and other objects in view which will be more apparent as the specification proceeds, the invention resides in certain novel construction and combination and arrangement of parts, the essential elements of which are hereinafter fully described, are particularly pointed out in the appended 30 claims and are illustrated in the accompanying drawing, in which:—

Figure 1 is an interior elevation of my improved cleaning device.

Figure 2 is a vertical sectional view of 35 the same.

Figure 3 is a detail perspective view of the connecting joint.

Referring to the drawing in detail, 10 represents a frame which may be made of cast 40 metal or other suitable material and which is provided with interior and exterior upwardly extending arms 11 and 12 respectively and is formed at its base with grooves 13 and 14 whereby the frame 10 may be 45 clamped to the stop of the window frame either in position to receive the upper sash or to receive the lower sash. In cases where the bottom of the window frame is not provided with an upwardly extending stop, any 50 suitable cleat of wood or other desired material may be secured to the window frame as a substitute for the stop.

Mounted for rotation in suitable bearings in the upper ends of arms 11 and 12 are 55 stub shafts 15 and 16 carrying at one end a gear wheel 17 and at the other sprockets

18. Mounted on the shafts 15 and 16 so as to enclose the gear wheels 17 are housings 19 which also hold rods 20 formed with racks 21, so that said racks engage the respective gears 18. Mounted at the outer end of each member 20 is a horizontal spring pressed rod 22 carrying at its end a cleaning member 23 the cleaning members being 60 pressed toward the window glass by means of springs 24. Mounted on the member 20 carried by the arm 11 is a finger piece 25 whereby the rod 20 may be moved to carry the cleaning member 23 over the glass of 65 the window.

It will be noted that the cleaning members 23 are formed with a pointed outer end so as to reach all portions of the window, said cleaning member and their rods 22 being prevented from rotation by the rods being of square cross-section and mounted in square openings in bosses at the ends of the members 21. The sprockets 18 are connected by chains or belts 26 with lower sprockets 27 and 28 mounted on the ends 80 of a shaft 29 having its bearings in the frame 10. A guide member 30 is mounted on trunnion bearings in the frame 10 and is provided with upwardly extending arms 31 having guide members 32 at their upper 85 ends. Connecting rods 33 are secured to cranks formed on a crank shaft 34 rotatably mounted in the frame 10, and extend through the guides 32 being pivotally connected at their upper ends with pins 35 secured to the faces of the guide members 19. By providing the frame 30 with trunnions as described and as shown at 30° the trunnions mounted in the frame 10, it follows 90 that said frame 30 compensates for movements of the connecting rods 33 on rotation of the crank shaft 34.

In operation the lower window sash is thrown up, then the frame 10 is secured to the window stop either at the groove 13 or 100 the groove 14 according to whether it is the upper or lower window that is to be cleaned. The cleaning members 23 are provided with suitable clothes or sponges and are separated, after which the window sash is pulled down and the members 23 are released so that they are pressed against the window by their springs 24. The operator now grasps the knob 25 and moves the inner cleaning member 23 over the inner surface of the 110 window. The movement of the member 20 in the sheath 19 will be communicated to

the smaller exterior parts by means of the gears, sprockets and belts; and any rotary movement of the inner member 19 on the pivot 15 will be communicated to the outer member 19 by means of the crank rods 33 and crank shaft 34. This is because pins 35 are below the centers 15 and 16 and when the inner member 19 is rotated about center 15, its pin 35 will cause inner rod 33 to effect such rotation of shaft 34 as will through outer rod 33 and its pin 35 effect the same rotation of the outer member 19 about its center 16.

What is claimed as new is:—

15 1. In a device of the class described, the combination of a pair of cleaning pads, manipulating rods formed on each of said pads, means on said rods for forcing the pads toward each other, gear racks connected to each of said rods, a gear meshing with each of said racks, a sprocket operable by each of said gears, means whereby movement may

be communicated from one of said sprockets to the other of said sprockets, and supporting means for the aforesaid mechanism. 25

2. In a device of the class described, the combination of a pair of cleaning pads, manipulating rods formed on each of said pads, means on said rods for forcing the pads toward each other, gear racks connected to each of said rods, a gear meshing with each of said racks, a sprocket operable by each of said gears, means whereby movement may be communicated from one of said sprockets to the other of said sprockets, a sheath for each of said rack bars, connecting rods having one end connected to each of said sheaths and the other end to a crank shaft, supporting means for the aforesaid mechanism as and for the purpose specified. 30 35 40

In testimony whereof I have affixed my signature.

FENWICK FAYETTE SAXE.
